UNITED STATES PATENT OFFICE.

DOMENICO CONTENTO, OF NEW YORK, N. Y.

EYEGLASSES.

1,338,174.

Specification of Letters Patent. Patented Apr. 27, 1920.

Application filed January 2, 1920. Serial No. 348,791.

To all whom it may concern:

Be it known that I, DOMENICO CONTENTO, a citizen of the United States, residing at New York city, in the county of New York, 5 State of New York, have invented certain new and useful Improvements in Eyeglasses; and I do hereby declare the following to be a full, clear, and exact description of the invention, such as will enable others skilled in the art to which it appertains to 10 make and use the same.

This invention relates to optics, and more especially to eyeglasses; and the object of the same is to improve the mechanism for 15 permitting folding of the glasses and latching of the same in overlapped position.

To this end the invention consists specifically in a novel form of catch as will be described below and as shown in the drawings 20 wherein:

Figure 1 is an elevation of a pair of eyeglasses equipped with this invention, the same being open.

Fig. 2 is an enlarged section through the 25 glasses when folded, and through the catch which holds them in folded condition.

Fig. 3 is a detail showing certain parts of the catch.

The lenses L are mounted within bows B 30 which are connected by a spring S and carry the usual nose pieces N, and in the present construction one bow has a handle H and the other has a keeper K adapted to engage the catch on the handle when the lenses are 35 folded one over the other. It is the particular construction of this catch which forms the subject matter of the present invention.

The numeral 1 designates a box shaped casing open at its front end and having a 40 notch 2 in its upper edge, and this casing is adapted to be inserted into a suitable recess 3 within the handle H and held therein by suitable means such as a screw 4.

The numeral 11 designates a bolt slidably 45 mounted within the casing and projecting out its open end and carrying a knob 10, and the upper edge of this bolt has a notch 12 adapted to aline with the notch 2 when the bolt is borne inward against the tension 50 of a spring 13, the latter preferably standing within a cavity 14 in the inner end of the bolt and resting on the bottom of the casing. The bolt also has a slot 15 engaged by a pin 16 fixed transversely across the casing, the 55 slot being of a length to permit the spring

to throw the notches normally out of register or to permit pressure on the head 10 of the bolt to bear the latter inward and throw the notches into register.

This entire structure is mounted in the 60 recess 3 in the handle as stated, its notch 2 facing toward the bow B which carries said handle and yet spaced therefrom a sufficient distance to permit the passage of a tongue 17 which projects from the keeper K, so that 65 as the glasses are folded the tongue will be projected through the notch 2. This tongue tapers to its tip as at 18 and its body is notched as at 19. In its passage through the notches 2 and 12 it causes the bolt to slide 70 inward and compress the spring 13, and when its notch 19 has passed the bolt, the latter is projected by its spring as far as the length of its slot 15 will permit, and the tongue is fastened so that the glasses are 75 held in this condition. To open them, it is only necessary to press on the head or knob 10, and when the latch releases the tongue of the keeper, the spring S causes the glasses to fly open. 80

Attention is invited to the fact that all parts of this device are movably mounted in the recess 3 in the handle by a single fastening means such as the screw 4, and when the catch needs attention by way of 85 cleaning or repair, it is taken bodily out of the handle for that purpose. Such handle may be of shell or precious metal, and it is obviously wise to remove all mechanism therefrom while working on it so that the 90 handle will not be heated or accidentally struck or scratched by the tools. While I have shown the casing 1 as substantially rectangular, it may be given other external configuration so as to adapt it to a recess 3 95 of appropriate shape. Whatever the material of the handle, it is only necessary to provide it with this recess and with the little hole into the bottom of the recess for the passage of the fastening device 4, and therefore work on an expensive handle is minimized with a consequent reduction in the chances of breaking it. 100

What is claimed as new is:

A folding eyeglass frame including a 105 keeper on one lens bow having a notch in one edge and a tapered tip; combined with a handle on the other bow provided with a recess, a box-like casing having a notch across one edge and open at its outer end, 110

a screw through the handle into the bottom of said casing, a bolt slidably mounted in the casing and having a notch across one edge adapted to align with that mentioned and a longitudinal slot in its body and a cavity in its lower end, its outer end projecting beyond the casing and having a knob, an expansive spring within said cavity resting on the bottom of the casing, and a pin

across the casing through said slot, for the purpose set forth.

In testimony whereof I affix my signature, in the presence of two witnesses.

DOMENICO CONTENTO.
